INVENTOR.

GEORGE A. WEINGARTNER
BY *James V. Ramey*

ATTORNEY.

UNITED STATES PATENT OFFICE

GEORGE A. WEINGARTNER, OF FORT THOMAS, KENTUCKY, ASSIGNOR TO THE WADSWORTH WATCH CASE COMPANY, OF DAYTON, KENTUCKY, A CORPORATION OF KENTUCKY

WATCHCASE

Application filed March 31, 1931. Serial No. 526,630.

This invention relates to watchcase construction and more specifically to a waterproof crown structure.

In the patent to Georges Perret, No. 1,661,232, granted March 6, 1928, is disclosed a crown structure for watchcases to effect tightness of the joints between the crown, the winding stem and the watchcase. The device shown in this patent has several serious defects in that the packing member 16 is visible at all times and being of an elastic material impermeable to water it does not harmonize with the exterior finish of the watchcase; also the screws 9 and 10 and the threaded openings therefor in the crown 8 are likewise visible at all times and it is well-known to those skilled in the art of watchcase construction that a screw thread, regardless as to its accuracy in manufacture, is a passage easily penetrated by water. The openings for these screws 9 and 10 are also unsightly and detract from the finished appearance of the crown 8 due to the fact that the threaded openings for said screws would show the base metal of the crown unless the crown were made of solid precious metal or plated after the threads were cut.

My invention seeks to overcome the defects inherent in a crown structure for watchcases of the kind just described, by providing a reorganization and arrangement of parts whereby no base metal of the crown or associated parts is exposed or any pliable gaskets are exposed, nor does the crown have any exposed threaded openings or screws therein which, as above pointed out, become passages easily penetrated by water.

Other objects of my invention are to provide a waterproof crown construction for watchcases which is simple, efficient, economical to manufacture and highly satisfactory in accomplishing its intended purposes, to-wit: preventing water, dust and like foreign matter from entering the watchcase at the opening for the winding stem.

A further object of this invention is to have all of the parts concealed by the crown when the latter is screwed upon the case.

A still further object is to so construct and arrange the parts in a manner permitting

the sealing gasket to be located between the crown tube and the crown proper and carried and concealed by the latter at all times.

The present invention consists in providing a crown tube rigidly attached to the movement ring and having a screw threaded engagement with the crown, of a sealing gasket located between said tube and crown, of a winding stem sleeve screwed to the winding stem and having a non-circular head which is adapted to be received by a non-circular socket in the crown whereby any rotation of the latter is imparted to the winding stem through said sleeves, of a retaining washer fixed to the crown to imprison the noncircular head of the winding sleeve within the non-circular socket in the crown and of an expansion spring located between the sleeve and crown to normally force the crown in a direction away from the winding stem.

The invention further consists in the construction, combination, location and arrangement of parts, all as will be hereinafter more fully set forth and claimed.

Referring to the accompanying drawing which is made a part hereof and on which similar reference characters indicate similar parts—

Fig. 1 is a greatly exaggerated sectional view of one embodiment of the invention, the crown being illustrated in the sealed position;

Fig. 2 is a similar view, the section being taken on a plan different to that of Fig. 1 and illustrating the crown in the unsealed position or in a position whereby winding of the movement and setting of the hands can be accomplished;

Fig. 3 is an isometric view of the crown, one-quarter section being removed to clearly illustrate its construction;

Fig. 4 is an isometric view of the winding stem sleeve, one quarter section of which is removed to show its construction;

Fig. 5 is an isometric view of the crown gasket and washer likewise partially broken away;

Fig. 6 is an isometric view of the crown-

tube, one quarter section being broken away to show its construction;

Fig. 7 is an isometric view illustrating a modified construction of the crown washer, 5 one quarter section being removed to show the external thread thereon; and

Fig. 8 is a bottom view of the crown showing the square socket therein.

There are two types of movements now 10 used in watches, one type of which carries the winding stem and the other type of which has provision for receiving the stem, the stem being carried by and forming a part of the watchcase.

15 The present invention relates to a waterproof crown for the former type, that is a movement having the stem constructed as a part thereof. In both types, however, it is necessary to rotate the winding stem for 20 winding the mainspring of the movement, in addition to moving the stem axially for the purpose of setting the hands.

25 Referring to Figs. 1 and 2, 9 designates a part of the watchcase which, in this instance, represents the center or movement ring, 10 designates the crown tube, 11 the crown, 12 the winding stem sleeve, 13 the winding stem, 14 the retaining washer, 15 the gasket and 16 the crown expansion 30 spring.

35 Referring more in detail to the above-mentioned parts, the crown tube 10 is preferably cylindrical in form, as shown in Fig. 6, and is provided with an internal annular flange 17 at its bottom and with an external annular flange 18 at its top. The outer periphery of the last-mentioned flange is provided with a left-hand external screw 40 thread 19 which is adapted to receive the internal left-hand screw thread 20 of crown 11 in a manner presently to be described. The crown tube 10 is further provided with a central bore 21 and a communicating central bore 22, said bore 22 being of a smaller 45 diameter than the bore 21 through which the winding stem 13 is adapted to be passed, the bore 21 being of a size suitable for receiving the lower portion of the winding stem sleeve 12, as clearly illustrated in Figs. 50 1 and 2. The lower part of crown tube 10 is received within an opening 9a in the part 9 of the watchcase and securely fixed therein in any suitable manner, as, for example, by solder 23. Thus the crown tube 10 becomes a fixed part of the watchcase center, 55 as shown in Figs. 1 and 2, this part 9 in the present instance being the movement holding means or center, as above stated.

60 Referring next to the winding stem sleeve 12 and especially to Fig. 4, it will be seen that the upper end of said sleeve has a square head 24 formed integral therewith, the sleeve being provided with a spring receiving recess 25, which recess is separated 65 from the internally threaded socket 26 by

the partition 27 formed as an integral part of the winding stem sleeve 12. The internal right-hand threaded socket 26, of winding stem sleeve 12, receives the right-hand external thread formed on the outer end of the winding stem 13, and when sleeve 12 is screwed home upon the outer end of the winding stem 13 (or until the outer end thereof comes to rest against the partition 27) any clockwise rotation of said winding stem sleeve will be imparted to said winding stem 13. As shown in Fig. 1, the gasket 15 is preferably made of a flexible pliable material impervious to water, such as cork, and the washer 14 is preferably made of a metal. 70 Crown 11 is provided with a square socket 29 adapted to receive the square head 24 of winding stem sleeve 12. 75

80 In assembling the parts comprising the waterproof crown and associated part, the first operation is that of soldering the crown tube 10 to the center or movement ring 9 of the watchcase with solder at 23, or otherwise permanently attaching said crown tube to said watchcase. Then insert the expansion spring 16 within the spring receiving recess 25 and place the square head 24 of winding stem sleeve 12 within the square socket 29 of crown 11. Then insert the washer 14 over the winding stem sleeve 12 and within the crown 11. Then solder or otherwise attach at 30 the metal gasket 14 to the internal annular shoulder 28 of crown 11. Then place the pliable gasket 15 upon the top face of external annular flange 18 of crown tube 10. Then insert the outer threaded end of the winding stem 13 within the internal threaded socket 26 of winding stem sleeve 12 and rotate the crown in a clockwise direction, thus screwing the threaded end of said winding stem within the winding stem sleeve 12 until the end of said stem 13 is screwed home against the partition 27 of the winding stem sleeve 12. 90

95 To wind the watch and set the hands, the crown 11 is unscrewed from the crown tube 10 by rotating it in a clockwise direction, or in a direction suitable for winding. When the crown 11 is separated from the crown tube 10, spring 16 moves the latter 100 into the position shown in Fig. 2, at which time the washer 14 is brought against the square head 24 of winding stem sleeve 12, thus limiting the outward movement of said crown. 110

115 With the crown 11 thus separated from the crown tube 10, the mainspring of the movement can be wound by rotating the crown in a clockwise direction and if the user desires to set the hands he may do so by pulling outwardly upon the crown 11 120 whereupon the washer 14 will pull outwardly upon the square head 24 of the winding sleeve 12, which sleeve in turn pulls outwardly upon the winding stem 13 in order to bring the winding stem and the mecha- 125

nism which it operates to a setting position.

After either of the operations of winding the main spring of the movement or setting of the hands has been accomplished, all that is necessary to seal the joint between the crown 11 and the crown tube 10, is to press inwardly upon said crown against the compression of spring 16 and rotate it in an anti-clockwise direction, whereupon the internal screw thread 20 of the crown 11 will be screwed upon the external thread 19 of the crown tube 10 at which time the sealing gasket 15 will be concealed within said crown and tightly wedged between the washer 14 and the upper surface of flange 18 of the crown tube 10, as clearly shown in Fig. 1.

While I have shown the washer 14 soldered within the crown 11, as at 30, in Figs. 1 and 2, it will be understood that said gasket could be supplied with an external thread 14a, as shown in Fig. 7 and with spanner wrench sockets 14b, if desired, so that said washer, instead of being soldered to crown 11, could be screwed therein, the thread 14a of the washer being received by the internal screw thread 20 of said crown, as will be clearly apparent from the drawing.

It will be obvious to those skilled in the art that various changes may be made in my waterproof crown construction without departing from the spirit of the invention and I do not, therefore, limit myself to what is shown in the drawing and described in the specification, but only as set forth in the appended claim.

Having thus fully described my said invention, what I claim as new and desire to secure by Letters Patent is:

A new and improved waterproof crown structure for wrist watchcases of the type wherein the winding stem is formed as a part of the watch movement comprising the combination of a wrist watchcase, a crown tube soldered thereto, an external left hand thread cut upon the outer end of said tube, a crown provided with an internal non-circular socket, an internal left hand thread cut in said crown, a shoulder formed within said crown and located between said socket and thread thereof, a retaining washer fixed within said crown, a winding stem sleeve having its inner end internally threaded to receive the threaded outer end of a winding stem, an enlarged non-circular head formed upon the outer end of said sleeve, a resilient gasket located between said crown and said crown tube, and a spring received within a bore in the outer end of said winding stem sleeve and adapted to normally exert outward pressure against said crown characterized by the fact that said non-circular head of said winding stem sleeve is imprisoned within the non-circular socket in

said crown by said retaining washer and that said crown when free from said crown tube is permitted to move axially relative to said sleeve but compelled to rotate therewith, and that by screwing said crown upon said crown tube the resilient gasket is compressed between said retaining washer and tube to form a watertight joint substantially as described and for the purposes set forth.

GEO. A. WEINGARTNER.
